EXPLODING SHELL.

1,096,734.

Specification of Letters Patent. Patented May 12, 1914.

Application filed November 22, 1909. Serial No. 529,343.

To all whom it may concern:

Be it known that I, HEINRICH MAYER, engineer, a subject of the German Emperor, residing at 15 Frankenstrasse, Dusseldorf, 5 Germany, have invented new and useful Improvements in Exploding Shells, of which the following is a specification.

This invention relates to improvements in exploding shells, and more particularly to 10 that class of shells in which a bombshell is provided in front of a shell containing a shrapnel charge and in which, in case of a shrapnel shot, the bomb shell is thrown from the shrapnel shell together with the bullets. 15 In shells of this class as heretofore constructed the bomb shell is screwed to the body of the shrapnel shell, in a similar way as in ordinary shells the head is usually screwed to the body. If the shrapnel 20 charge of such shells is caused to explode, the screw threaded joint between the bomb shell and the body of the shell is not always uniformly broken, the said connection sometimes breaking first at one side, and in such 25 cases the bombshell turns over and explodes prematurely, if it explodes at all. Furthermore, in most cases the head or grenade of such a shell is deflected from the proper trajectory in such a manner as to miss the 30 target and also to break up the cone of dispersion of the shrapnel shot.

The object of this invention is to provide a shell of this class in which the bombshell is uniformly torn from the shrapnel shell 35 all around its circumference, so that it does not turn over. And for this purpose the bombshell is not positively secured to the shrapnel shell, as by a screw-joint, but it is in frictional engagement therewith.

40 For the purpose of explaining the invention an example embodying the same has been illustrated in the accompanying drawing, in which the shell is shown in vertical cross-section.

45 As shown in the said drawing, *a* is the shrapnel shell which is filled with bullets *b*. In front of the latter the bombshell *d* made of thick walls is located which is filled with the bomb charge *c*. To the bomb shell a 50 fuse *e* is screwed which contains two igniting charges, one of which may ignite the bomb charge while the other fires the central train shown in the drawing, thereby igniting the shrapnel charge. A suitable contact fuse may also be arranged at the point

of the shell for igniting the bomb or grenade charge.

At its rear end the bombshell *d* is made with a reduced cylindrical portion of a smooth surface the diameter of which is 60 slightly larger than that of the corresponding bore of the shrapnel shell *a*, and the bombshell is forced into the shrapnel shell under high pressure. By properly choosing the difference of the diameters of the reduced portion of the bombshell and of the bore of the shrapnel shell, and the length of the said reduced portion, the connection between both parts is made of the desired 65 rigidity.

Having now particularly described and ascertained the nature of my said invention and in what manner the same is to be performed, I declare that what I claim is.

1. In a shell, the combination, with a body containing a shrapnel charge and a shrapnel filling, of a head containing a bomb charge, said head having a neck portion held in and to the body by friction only, a contact fuse for igniting the bomb charge, and a fuse 70 comprising a train for igniting the shrapnel charge.

2. In a shell, the combination, with a body containing a shrapnel charge and a shrapnel filling, said body having a smooth cylindrical open front end, of a head having a bomb charge, said head having a reduced neck portion fitting tightly into the said front end of the body, said head being held to the body by friction only, a contact fuse arranged to ignite the bomb charge, and a fuse 75 comprising a train arranged to ignite the shrapnel charge.

3. In a shell, the combination, with a body having an interiorly smooth cylindrical open front end, and a head containing a bomb charge, said head having a smooth neck portion fitting tightly into the open front end of the body and held to the body by friction only, of a plurality of shrapnel balls contained within said body and back of the head, a shrapnel charge carried by said body, a contact fuse arranged at the point of the shell to ignite the bomb charge, and a fuse comprising a train arranged to ignite 85 the shrapnel charge.

4. In a shell, a body having a smooth cylindrical interior open at its front end, said body also having an integral closed base, in combination with a head containing a bomb 90

charge, said head having a smooth neck portion fitting tightly into the open front end of the body, said head being held to the body by friction only, the exterior surface 5 of the head at the point of union with the body being flush with the exterior surface of said body, a plurality of shrapnel balls arranged within said body and back of said head, a shrapnel charge carried by said body 10 at the rear of said shrapnel balls, a contact fuse arranged at the point of the shell and

arranged to ignite the bomb charge, and a fuse comprising a train arranged to ignite the shrapnel charge.

In testimony whereof I have signed my 15 name to this specification in the presence of two subscribing witnesses.

HEINRICH MAYER. [L.S.]
